UNITED STATES PATENT OFFICE

LULA M. REINCKE, OF DENVER, COLORADO

DESIGN FOR A SOUP SPOON

Application filed June 5, 1931. Serial No. 40,096. Term of patent 14 years.

To all whom it may concern:

Be it known that I, LULA M. REINCKE, a citizen of the United States, residing at Denver, county of Denver and State of Colorado, have invented a new, original, and ornamental Design for a Soup Spoon, of which the following is a specification, reference being had to the accompanying drawings, forming a part thereof:

Fig. 1 is a front elevation of a soup spoon showing my new design; and

Fig. 2 is a side elevation of the same.

The essential feature of the design is an oval-shaped bowl secured to a handle in such manner that the greater dimension of the bowl is at a right angle to the handle, and having substantially the configuration and outline shown.

I claim:

The ornamental design for a soup spoon substantially as shown and described.

LULA M. REINCKE.
